UNITED STATES PATENT OFFICE.

SAMUEL M. PERRY, OF PLAINFIELD, NEW JERSEY.

IMPROVEMENT IN CORSETS.

Specification forming part of Letters Patent No. **56,794**, dated July 31, 1866; antedated July 20, 1866.

To all whom it may concern:

Be it known that I, SAMUEL M. PERRY, of the town of Plainfield, county of Union, and State of New Jersey, have invented a new and useful Improvement in Corsets, of which the following is a full, clear, and exact description thereof, reference being had to the accompanying drawings, forming a part of this specification, in which—

Figure 1 represents a front elevation of my improved corset, and shows the corset-fastening unlooped at the top, as hereinafter specified. Fig. 2 is a front elevation, showing metal stud and loop-plates, which I use to clasp and unclasp the improved corset, separated from the rest of the corset; and it is in the improved construction of these parts that my invention mainly consists.

Like letters of reference refer to like parts in both the figures.

A A' is the stud-plate; B B', the loop-plate; C C', the cloth bodice of the corset; D D', the lacing-cord, by which the corset is fitted to the wearer's person.

The lacing-cord D D' is the ordinary and well-known device heretofore in use for that purpose, as is also the bodice C' C', which is stiffened by upright springs in the usual manner; yet any improved devices may be substituted for these constructions.

My improvements, as before stated, relate mainly to an improved construction and operation of the clasp-plates A A' and B B' and the parts C' C' of the bodice immediately adjacent thereto, and are designed not only for the use of the common wearers of corsets, but also for nursing-women, invalids, and corpulent persons who cannot without great inconvenience or suffering wear corsets of the ordinary construction.

My improvement consists in furnishing one or both the clasp-plates A A' and B B' with a joint, E or E', which I place in any convenient point below the upper clasp-hook, F, and so construct the same that when the clasp hook or hooks above the aforesaid joints E or E' are released the part or parts of the clasp-plates

A and B to which they are attached are free to move outward and to right or left sufficiently to relieve the wearer or to expose the wearer's person for nursing, surgical treatment, &c.

The best construction for general use of this my invention known to me, and the one fully shown in the drawings accompanying this specification, has two hinges, E E', which I place diagonally, as shown in the drawings, one on each of the clasp-plates A A' and B B'.

G G' G'' G''' are four loop-plates, of ordinary device, attached to the plate B B' by rivets in the usual manner, and these loop to the four stud-heads H H' H'' H''', of ordinary device, and attached to the clasp-plate A A'. Now I place the diagonal hinges E E' just above the second loop, G'' H'', so that G H G' H', the tops of either side of the corset, may be swung outward and downward, as fully shown at A G G' E in both figures of the drawings.

The clasp-plates A A' and B B' are each constructed in two parts to admit the free working of the hinge-joints E and E', parting at said joints, while the upper parts of the bodice C C', being of the usual flexible construction and material, fully admit of the free working aforesaid and complete the form of my device I most approve.

Having thus described my invention, what I claim, and desire to secure by Letters Patent of the United States, is—

A corset having one or more jointed clasp-plates so constructed, essentially as herein specified, that the top ends of said clasp-plates may swing outward and downward when the tops of said clasp-plates are unloosed, and afford a ready access to the parts of the wearer's person thereby exposed, while the bottom ends of said clasp-plates serve to clasp the corset sufficiently when the top is unloosed.

SAMUEL M. PERRY.

In presence of—
HUGO SCHNEELOCK,
E. GODDARD.
